[57] **CLAIM**

The ornamental design for a removable writing surface and paper holder for wheelchair armrests, as shown and described.

DESCRIPTION

FIG. 1 is a top perspective view of a removable writing surface and paper holder for wheelchair armrests showing my new design with a wheelchair armrest shown in phantom lines for environmental purposes;

FIG. 2 is a top plan view thereof;

FIG. 3 is a front elevation view thereof, the rear elevational view being identical;

FIG. 4 is a bottom plan view thereof; and,

FIG. 5 is a right side elevational view thereof, the left side elevational view being identical.
